UNITED STATES PATENT OFFICE.

THOMAS F. REID, OF VANCOUVER, BRITISH COLUMBIA, CANADA.

BOILER.

Application filed October 9, 1924. Serial No. 742,655.

To all whom it may concern:

Be it known that I, THOMAS F. REID, a subject of the King of Great Britain, and a resident of the city of Vancouver, in the Province of British Columbia, Canada, have invented certain new and useful Improvements in Boilers, of which the following is a specification.

My invention relates to improvements in 10 boilers, with more particular reference to those used in hot water heating systems, although my improvements may be applied to steam boilers also, and the object of my invention is to provide a boiler of extremely 15 simple and strong construction in which the water heating is quickly effected and maintained with great economy and ease so that the entire system may be operated at a low cost and with great efficiency with the minimum of attention and labour.

I attain this object by the construction illustrated in the accompanying drawings in which—

Fig. 1 is an outside view of the boiler, in 25 side elevation.

Fig. 2 is a longitudinal sectional view taken through the centre line.

Fig. 3 is a front end view.

Fig. 4 is a rear end view.

Fig. 5 is a front end view with the front 30 end plate removed.

Fig. 6 is a fragmentary sectional view of the water-jacketed combustion chamber top.

Fig. 7 is a plan view of the supplemental 35 garbage-burning grate.

Similar figures of reference indicate similar parts throughout the several views.

1 and 2 indicate the front and rear end plates of the boiler, formed out of steel plate 40 of suitable thickness and suitably spaced apart, the front end plate 1 being provided with the ashpit door 3, furnace door 4, tube cleaning door 5 and sight or hand hole doors 6 and 7, these doors, of course, closing their 45 respectively identified openings in the plate, as is well known, while the rear end plate 2 is provided with a smoke outlet opening 8 to which is connected the chimney pipe 9, as shown in Figs. 1 and 2.

Extending longitudinally between the front and rear end plates adjacent their outer and lower edges are water pipes 10 50 and 11, these pipes being projected exteriorly of the plates and having their front ends capped, as at 12 and 13, while to their rear ends are fitted elbows 14 and 15 to

which vertical water return pipes 16 and 17 are connected, and between the pipes 10 and 11 and suitably supported thereon is the fire grate, indicated by the numeral 18, to which 60 access is had by opening the furnace door 4.

19 indicates a cylindrical water chamber disposed at a suitable height above the grate 18 intermediate the height of the boiler, which chamber is of less length than the 65 distance between the plates so that at the rear end is formed a combustion chamber 20 communicating with the firebox 21 while at the front end is formed a smoke box 22, the smoke box being separated from the firebox 70 by a plate 23, as shown in Fig. 2. The top of the combustion chamber is closed by a semi-circular plate 24, and secured to the plate 24 and spaced from it is a second semi-circular plate 25 so that when the space between the plates is supplied with water a 75 water-jacketed top 25^a for the combustion chamber is formed which also serves the purpose of an extra water chamber, forming an effective part of the heating system. 80

Fitted in the water chamber 19 and extending from end to end of the same are smoke tubes 26 which establish communication between the combustion chamber 20 and the smoke box 22, while connecting the water chamber 19, towards its front and rear ends, with the longitudinal pipes 10 and 11 are pipes 27—28 and 29—30, these pipes, on opposite sides, that is, 27—29 and 28—30, being in turn connected with pipe coils 31 and 32 respectively, in the manner shown in Fig. 2.

33 indicates an upper cylindrical water chamber disposed above the chamber 19 and spaced therefrom to provide a flue 33^a, 95 which chamber abuts at its front end the front end plate 1 while at its rear end it is spaced from the rear end plate 2, as at 34, the rear end of this chamber 33 preferably lying in the same vertical plane as the rear end of chamber 19. Chamber 33 is connected to chamber 19 by vertical pipes 35 and 36 spaced apart longitudinally, as shown in Fig. 2, and it is provided on its upper side with a large T member 37 fitted 100 with water outlet connections, indicated by the numeral 38, and with a safety valve 39.

40 indicates a pipe connection between the rear end of the water chamber 33 and the water jacket 25^a, while 41 indicates a 110 pipe connection between the water jacket and the pipe 10. The entire construction

described in the foregoing, with the exception of the T member 37, is enclosed by a sheet metal covering 42 over a layer of asbestos 43, as shown in Fig. 5.

5 In operation the flame, hot gases, and smoke pass from the firebox rearwardly into the combustion chamber 20, forwardly through the smoke tubes 26 into the smoke box 22, and then rearwardly again through 10 the flue 33^a into the space 34 and out into the chimney 9, from which it will be seen that the entire water body, as contained in the pipes 10 and 11, pipes 27-28 and 29-30, coils 31 and 32, and the water chambers 19, 15 25^a, and 33, and which is relatively small as compared with the amount of heating surface, is subjected to the most intense heat so that the water is quickly heated and maintained at a high temperature with the 20 minimum expenditure of labour and fuel.

Should it be desired to burn garbage or other refuse a supplemental grate may be added into the firebox which grate consists of longitudinal pipes 44 and 45 extending 25 between and connected at their opposite ends to the pipes 27-28 and 29-30, between which pipes 44 and 45 extends a horizontal pipe coil 46 connected to them in the manner shown in Fig. 7, this coil forming a grate 30 on which the garbage may be thrown and burned and providing at the same time an economical means of securing additional heat.

From the foregoing it will be seen that I 35 have devised a simple and strongly constructed boiler capable of being used for heating purposes with great facility and efficiency and operated and maintained at a low fuel and labour cost.

40 What I claim as my invention is:

1. A boiler comprising front, rear, and side plates enclosing a furnace, a pair of pipes extending longitudinally on each side of the furnace adjacent the outer and lower edges of the front and rear plates and projecting through the same their front ends being capped and their rear ends elbowed, a cylindrical water chamber intermediate the height of said front and rear plates shorter than the distance between them whereby a smoke box and a combustion chamber are formed at the front and rear ends respectively of the said water chamber, plates forming the bottom and top of the said smoke box and combustion chamber respectively, smoke tubes extending through the said water chamber connecting the combustion chamber with the smoke box, an upper cylindrical water chamber disposed above the intermediate one abutting the front plate at its front end and spaced from the rear plate at its rear end provided with tubular connections on its lower side connecting it with the intermediate water chamber and on 60 its upper side with a T member having out-

lets, and tubular connections between the intermediate chamber and the aforesaid longitudinal pipes.

2. A boiler comprising front, rear, and side plates enclosing a furnace, a pair of 70 pipes extending longitudinally on each side of the furnace adjacent the outer and lower edges of the front and rear plates and projecting through the same their front ends being capped and their rear ends being 75 elbowed, a cylindrical water chamber intermediate the height of said front and rear plates shorter than the distance between them whereby a smoke box and a combustion chamber are formed at the front and rear ends respectively of said water chamber, plates forming the bottom and top of said smoke box and combustion chamber respectively, smoke tubes extending through 80 said water chamber connecting the combustion chamber with the smoke box, an upper cylindrical water chamber disposed above the intermediate one abutting the front plate at its front end and spaced from the rear plate at its rear end provided with tubular connections on its lower side connecting it with the intermediate chamber and on its upper side with a T member having outlets, and a pair of spaced tubular connections between 85 each of the aforesaid longitudinal pipes and the intermediate water chamber, the members of each pair being connected by a pipe coil.

3. A boiler comprising front, rear, and side plates enclosing a furnace, a pair of 100 pipes extending longitudinally on each side of the furnace adjacent the outer and lower edges of the front and rear plates and projecting through the same their front ends being capped and their rear ends elbowed, a cylindrical water chamber intermediate the height of said front and rear plates shorter than the distance between them whereby a smoke box and a combustion chamber are formed at the front and rear ends respectively of the said water chamber, a plate 105 forming the bottom of the smoke box between the front plate and the front end of the water chamber, a plate forming the top of the combustion chamber between the rear plate and the rear end of the water chamber on which is superposed another plate, both plates enclosing a space adapted to form a water-jacketed top for the combustion chamber, smoke tubes extending through the water chamber connecting the combustion chamber with the smoke box, an upper cylindrical water chamber disposed above the intermediate one abutting the front plate at 110 its front end and spaced from the rear plate at its rear end provided with tubular connections on its lower side connecting it with the intermediate water chamber and on its upper side with a T member having outlets, 115 a pair of spaced tubular connections between 120 the intermediate water chamber and the aforesaid upper cylindrical water chamber, the members of each pair being connected by a pipe coil.

each of the aforesaid longitudinal pipes and the intermediate water chamber, the members of each pair being connected by a pipe coil, and a pipe connection connecting the combustion chamber water-jacket top with the upper water chamber and one of said longitudinal pipes.

4. A boiler comprising front, rear, and side plates enclosing a furnace, a pair of 10 pipes extending longitudinally on each side of the furnace adjacent the outer and lower edges of the front and rear plates and projecting through the same their front ends being capped and their rear ends elbowed, a 15 cylindrical water chamber intermediate the height of the front and rear plates shorter than the distance between them whereby a smoke box and a combustion chamber are formed at the front and rear ends respectively of said water chamber, a plate forming 20 the bottom of the smoke box between the front plate and the front end of the said water chamber, a plate forming the top of the combustion chamber between the rear 25 plate and the rear end of the water chamber on which is superposed another plate, both plates enclosing a space adapted to form a

water-jacketed top for the combustion chamber, smoke tubes extending through the water chamber connecting the combustion 30 chamber with the smoke box, an upper cylindrical water chamber disposed above the intermediate one abutting the front plate at its front end and spaced from the rear plate at its rear end provided with tubular connections on its lower side connecting it with the intermediate water chamber and on its upper side with a T member having outlets, a pair of spaced tubular connections between each of the aforesaid longitudinal 35 pipes and the intermediate water chamber, the members of each pair being connected by a vertically arranged pipe coil, a horizontally arranged pipe coil between and in connection with the said spaced tubular connections disposed intermediate the longitudinal pipes and the intermediate water chamber, and a pipe connection connecting the combustion chamber water-jacket top with the upper water chamber and one of 40 the said longitudinal pipes.

Dated at Vancouver, B. C., this 25th day of September, 1924.

THOMAS F. REID.
